(57) **CLAIM**

The ornamental design for neckwear to house and display metallic bars, as shown and described.

DESCRIPTION

FIG. 1 is a front view of a first embodiment of neckwear to house and display metallic bars showing my new design; FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front perspective view thereof;

FIG. 8 is a front view of a second embodiment of neckwear to house and display metallic bars showing my new design;

FIG. 9 is a rear view thereof;

FIG. 10 is a right side view thereof;

FIG. 11 is a left side view thereof;

FIG. 12 is a top view thereof;

FIG. 13 is a bottom view thereof;

FIG. 14 is a front perspective view thereof;

FIG. 15 is a front view of a third embodiment of neckwear to house and display metallic bars showing my new design;

FIG. 16 is a rear view thereof;

FIG. 17 is a right side view thereof;

FIG. 18 is a left side view thereof;

FIG. 19 is a top view thereof;

FIG. 20 is a bottom view thereof;

FIG. 21 is a front perspective view thereof;

FIG. 22 is a front view of a fourth embodiment of neckwear to house and display metallic bars showing my new design;

FIG. 23 is a rear view thereof;

FIG. 24 is a right side view thereof;

FIG. 25 is a left side view thereof;

FIG. 26 is a top view thereof;

FIG. 27 is a bottom view thereof; and,

FIG. 28 is a front perspective view thereof.

(Continued)

The broken lines shown in the drawings illustrate portions of the neckwear to house and display metallic bars that form no part of the claimed design.
